UNITED STATES PATENT OFFICE.

ALWILL URBAHN, OF PATERSON, NEW JERSEY, ASSIGNOR OF ONE-HALF
TO ABRAHAM G. JENNINGS, OF BROOKLYN, NEW YORK.

FIGURED FABRIC.

SPECIFICATION forming part of Letters Patent No. 289,582, dated December 4, 1883.

Application filed April 5, 1883. (Model.)

To all whom it may concern:

Be it known that I, ALWILL URBAHN, of Paterson, county of Passaic, State of New Jersey, have invented an Improved Figured Fabric, of which the following is a specification.

Figure 1 represents a sectional elevation of the loom on which my improved figured fabric is made. Figs. 2, 3, 4, 5, and 6 are face views of the fabric.

10 This invention relates to an open figured fabric of the kind described in my application for a patent known as "Serial No. 79,687," which was filed on the 19th day of December, 1882.

15 The invention consists more particularly in carrying the figure-thread which forms the design diagonally on opposite sides of the body-threads, which are composed of cross-woven warp-threads and of shuttle-threads, so that 20 on each side of the fabric a separate design formed by the figure-thread will be produced, and yet only one series of figure-threads employed. The fabric is therefore reversible.

25 For making this fabric I may use the same kind of loom that is described in said application filed December 19, 1882, and of which a portion is shown in Fig. 1.

30 In Fig. 1, the letters *ab* represent the ground warp-threads, that are taken from a beam and passed through the heddles *C D*, which heddles have needle-like projections *d*, described and more fully shown in my above-mentioned application, said projections being perforated near the ends, to admit said ground warp-threads.

35 *H* represents the shuttle, which carries the shuttle-threads *i* between the warp-threads *a b*, in the manner more fully indicated in Fig. 12 of my above-mentioned application. The 40 figure-cords *ff* are carried through heddles *N N* and then between downwardly-projecting pillars *g* of the upper reed, *P*. Each of the heddles *N* has downwardly-projecting needle-like bars *d*, like those of the heddles *C* and *D*, 45 and the figure-cords are drawn through the holes that are near the free ends of these needle-like bars. The upper reed, *P*, is suspended from the framing in such a manner that it is capable of slight lateral motion.

50 Now, in order to lay these figure-cords according to the present invention, they are first

tied by some of the shuttle-threads to the upper face of the ground fabric, and then afterward by other shuttle-threads to the lower face of said ground fabric—that is to say, while the heddles *N N*, or such of them as may be needed for the purpose, are above the warp-threads *a b*, the open ground fabric alone will be formed and part of the figure-cords held freely above such ground fabric. The figure-cords are then carried down into the lower part of the shed and tied by one or more of the shuttle-threads to the ground fabric, and then the figure-cords are kept under the shed, as indicated in Fig. 1, and more of the ground fabric is made above them until the figure-cords are again raised into the shed to be tied by one or more shuttle-threads, and then the figure-cord is again carried over the warp-threads *a b*, and so on, thus producing an open 60 fabric which shall have part of the same figure-cords *f* on one face and part on the other face thereof. The result will be a different design, according to the greater or less degree of lateral motion imparted to the heddles *N N* during the progress of the weaving, and the 65 design produced will invariably be a more or less broken figuring, such as is indicated in Figs. 2, 3, 4, 5, and 6. The figure-cord can be seen throughout when the fabric is held 70 against the light.

Fig. 3 shows the reverse of the fabric shown in Fig. 2; Fig. 5, the reverse of that shown in Fig. 4. Where the figure-cords are bent to an angle at the time they traverse from one side 85 of the ground fabric to the other, as in Fig. 6, these angles should be held by the ground warp-threads *a b*, as indicated in Fig. 6.

I claim—

As a new article of manufacture, the reversible open fabric composed of longitudinal cross-woven ground warp-threads *a b*, transverse ground shuttle-threads *i*, and of the figure-cords *ff*, that are placed in alternate sections on opposite sides of the ground fabric, to produce separate and distinct designs on each face of the fabric, substantially as described.

ALWILL URBAHN.
